UNITED STATES PATENT OFFICE.

AMBROSE LENTATZ, OF WEST HOBOKEN, NEW JERSEY.

COLLAR-BUTTON.

1,352,754.

Specification of Letters Patent. Patented Sept. 14, 1920.

Application filed February 20, 1919. Serial No. 278,214.

To all whom it may concern:

Be it known that I, AMBROSE LENTATZ, a citizen of Italy, residing at West Hoboken, in the county of Hudson and State of New Jersey, have invented certain new and useful Improvements in Collar-Buttons, fully described and represented in the following specification and the accompanying drawing, forming a part of the same.

The object of the invention is to provide a collar button which can be easily inserted in the buttonholes of the shirt band and collar and which will even permit the buttoning of the collar with one hand, which will hold the collar securely, will permit very easy unbuttoning, and will not injure the buttonholes.

These and other objects are provided for in the structures shown in the accompanying drawing, which are representative embodiments of my invention. After considering these, it will be apparent that other modifications may be made within the principles of the invention, and I do not limit myself to details except as claimed.

Figure 1 is a side elevation showing a collar button embodying my invention inserted in the neck band of a shirt and in one buttonhole of a collar, and partly inserted in the other collar buttonhole.

Fig. 2 is a front elevation of the button in place in a fully buttoned collar.

Fig. 3 is a top plan view, the base, however, being shown in section.

Fig. 4 is a side view of another form of the invention.

Fig. 5 is a top view.

Fig. 6 is a front end view of the same.

The form of the invention shown in Figs.

1, 2 and 3 comprises a shank 1, head 2 and base 3. All these parts may be of metal and formed integral, or they may be of other suitable material, or formed separately, and suitably connected together. In the particular example shown, the shank 1 and head 2 are of metal and may preferably be integral. The base 3 is of bone, shell, or other desired metal, connected to the shank. The connection is made in the present example by providing the shank with a stem 4 extending beyond shoulders 5 formed on the shank. The stem 4 passes through a hole in the center of the base and is thereafter pressed or hammered to form an upset portion or flange 6 at the back of the base, which holds the base firmly in position against the shoul-

ders 5. The flange 6 preferably is accommodated in a recess 7 in the back of the base.

Preferably, the shank is relatively wide in a horizontal direction compared to its vertical thickness. This is conveniently provided for in the present embodiment by making the sides 1^a of the shank divergent from the point where the shank joins the head to the points where the shoulders 5 are formed. The vertical thickness of the shank is maintained the same throughout, as shown in Fig. 1, and this dimension is less than the width of the shank for at least a considerable part of its length, as shown in Fig. 3. 70

The head is preferably of approximately triangular form as viewed from the front. Its upper edge 8 is preferably substantially flush with the upper surface 9 of the shank, as indicated in Figs. 1 and 2. Close to the shank at each side of it the head has a portion 10, or shoulder, extending laterally a considerable distance from the shank. The lower end of the head is formed into a rounded point 11. The back of this point is preferably beveled away at 12, Fig. 1, so as to "sharpen" the point for easier insertion into the buttonholes, as will appear.

At the place where the upper surface of the shank and the front surface of the head 85 intersect, the material is formed so that this intersection is a curve 13 of small radius.

The beveled point 11 of the head is easily inserted in the neck band buttonholes of a shirt and is shown in inserted position in Fig. 1 with the shank 1 extending through the buttonholes *a* and *b* of the band. These buttonholes grip the flat upper and lower sides of the shank where the shank is relatively wide near the base with sufficient force 95 to prevent the shank and head from rotating. One of the buttonholes *c* of the collar C has been passed over the head and is in place on the shank as indicated in Fig. 1, and the other buttonhole *d* is about to be 100 fastened. Fig. 1 shows how the lower edge *e* of the button hole may be hooked under the beveled point 11 of the head, and this may be done if necessary or desirable by using only one hand. By simply pulling 105 up on the collar, the head of the button will slip through the buttonhole until the upper edge *f* of the buttonhole passes the rounded surface 13 at the top of the head, and then the buttonhole will slide back and naturally 110 locate itself behind the head in the position shown in dotted lines in Fig. 1, and is

then held securely from accidental displacement by the side flanges or extensions 10, and by the lower overlapping portion of the head. To remove the collar, it is only necessary to pull the upper part of it slightly so that the upper edge *f* of the buttonhole slides forward of the head at the top, and then further downward pressure will immediately unhook the buttonhole from the head. The operations of buttoning and unbuttoning the collar may be performed with great rapidity and ease. The collar buttonholes slip on and off of the button so easily that there is no reasonable chance of injuring the buttonholes.

Figs. 4, 5 and 6 show a somewhat modified form of the invention in which the base 15 may be of metal and the head 16 may be substantially round. The entering edge 17 of the head may also be rounded and not beveled, although the head adjacent to this edge may be somewhat reduced in thickness, as indicated in Fig. 4. The shank 18 in this embodiment is formed with a part 19 adjacent to the head which is even wider than the shank of Figs. 1 to 3, to give greater security against turning of the button. This wide portion, defined by the parallel sides 20, extends considerably outwardly from the base to a point 21, where the width of the shank is reduced to the point 22, where the shank connects with the head. The sides 23 of the head, extending laterally considerably beyond the side edges 35 of the shank, securely retain the collar after it is buttoned. The manipulation of this device in buttoning and unbuttoning the collar is substantially the same as explained in connection with the other form of the invention.

What is claimed is:

1. A collar button, comprising a base, a shank, and a head connected at one of its sides to the outer end of the shank, the shank being narrow in a direction parallel to the vertical dimension of the head and

relatively much wider horizontally for at least part of its length.

2. A collar button, comprising a base, a head, and a shank, the head being approximately flat and thin in relation to its face-area, and being connected to the shank at one of its edges so that the head extends at substantially a right angle from one side of the shank, the shank being thin in a direction parallel to the direction in which the head extends from it and relatively wider near the base in a direction transverse that first mentioned.

3. A collar button, comprising a base, a head, and a shank, the head being approximately flat and thin in relation to its face-area, and being connected to the shank at one of its edges so that the head extends at substantially a right angle from only one side of the shank, the shank being thin in a direction parallel to the direction in which the head extends from it and relatively wider near the base in a direction transverse that first mentioned, the shank being narrower in the same direction near the head.

4. A collar button, comprising a base, a head, and a shank, the head being approximately flat and thin in relation to its face-area, and being connected to the shank at one of its edges so that the head extends at substantially a right angle from only one side of the shank, side portions of the head extending considerably laterally from the adjacent edges of the shank, the shank being thin in a direction parallel to the direction in which the head extends from it and relatively wider near the base in a direction transverse that first mentioned.

In testimony whereof I have hereunto set my hand in the presence of two subscribing witnesses.

AMBROSE LENTATZ.
